UNITED STATES PATENT OFFICE

2,460,521

DRAWER GUIDE

Robert H. McMurtrie, Huntingburg, Ind.

Application June 8, 1945, Serial No. 598,298

2 Claims. (Cl. 45—77)

1

My invention relates to improvements in drawer guides for the drawers of cabinets, bureaus, buffets, and the like, the primary object in view being to provide means of simple form and inexpensive construction for guiding drawers directly into casings and which is especially adapted to prevent sagging of drawers when the same are pulled open, and to compensate for warping of the sides of such casings, and to render opening and closing of drawers easy.

Other and subordinate objects, also comprehended by my invention, together with the precise nature of my improvements, will be readily understood when the succeeding description and claims are read with reference to the drawing accompanying and forming a part of this specification.

In said drawings:

Figure 1 is a view in transverse section illustrating my invention embodied in a cabinet, and a drawer,

Figure 2 is a view in longitudinal section with the drawer removed,

Figure 3 is a view in perspective of the drawer,

Figure 4 is a similar view of a portion of the right angled guide track, and

Figure 5 is a similar view of the other guide track.

Reference being had to the drawing by numerals, my invention has been shown therein, by way of illustration of the preferred embodiment thereof, as forming part of the equipment of a cabinet 1 having sides 2 and a top 3, and a drawer 4 provided with sides 5, a bottom 6, a front 7, and a back 8.

The drawer 4 is provided with a pair of lateral, exterior, guide flanges 9 extending along the upper edges of the sides 5. A pair of disk-like rollers 10 are suitably mounted on the sides 5 of the drawer 4, respectively, adjacent to the lower rear corners of said sides.

The sides 2 of the cabinet 1 are provided immediately below the level of the lower face of the top 3 with longitudinal, internal guide grooves 11 therein extending the full length of said sides, said grooves 11 accommodating the flanges 9 therein, whereby the drawer 4 is suspended at its top in the cabinet 1. At the front end of each guide groove 11, an anti-friction roller, as at 12, is suitably mounted on the side 2 of the cabinet 1, in a recess 13 in said side, with its top substantially level with the bottom of the guide groove 11.

A pair of channel guide tracks 14, 15 are countersunk in the inner faces of the sides 2 to

5 extend longitudinally parallel with the guide grooves 11 and in which the rollers 10 are adapted to ride. The guide track 14 is of right-angled form in cross-section, whereas the guide track 15 is substantially C-shaped in cross-section.

10 As will now be seen, by virtue of my invention, the drawer 4 when closed, is suspended in the cabinet 1 so that it cannot sag under weight therein, since it is supported by the flanges 9 in the guide grooves 11. Also, when the drawer 4 is pulled open, the flanges 9 and guide grooves 11 tend to prevent the drawer from sagging and the rollers 10, being at the rear, lower, side corners of the drawer 4 and prevented from upward play 15 by the guide tracks 14, 15, serve to prevent the drawer 4 from sagging, in conjunction with the flanges 9 and guide grooves 11, when said drawer 4 is pulled substantially completely open. The guide grooves 11 are deeper than the flanges 9 so as to obviate binding of said flanges in said grooves, should the sides 2 of the cabinet warp. The guide track 15 of C-shaped cross-section forms sides thereon designed to confine the roller 10 between the same against free lateral play so 20 as to prevent said roller from running out of said guide track 15 because of warping of the drawer 4 sidewise away from said guide track 15, and also because of deformation of said guide track 15 laterally resulting from warping of the adjacent side of 2 of the cabinet 1 outwardly. The right-angled cross-section guide track 14 is completely open at one side and is thereby designed to permit side play of the roller 10 therein so as to 25 compensate for warping of the drawer 4 sidewise away from the guide track 15, and also to compensate for lateral movement of the drawer 4 resulting from lateral deformation of the guide track 15. Thus, tendency of the drawer 4 to bind against the casing 1 at one side is compensated for at the other side thereof and in a manner tending to obviate binding at either side of said drawer. The rollers 12 provide for easily inserting the drawer 4 in the cabinet 1, and together with the rollers 10, for easy opening and closing 30 of said drawer.

40 The drawer 4 is preferably made in one piece of a suitable light, strong warp-proof plastic.

45 The foregoing will, it is believed, suffice to impart a clear understanding of my invention without further explanation of my invention.

50 Manifestly, the invention, as described, is susceptible of modification without departing from the inventive concept, and right is herein reserved to such modifications as fall within the scope of the appended claims.

What I claim is:

1. In combination, a casing having sides, a drawer having sides and a bottom, and means to mount said drawer on the sides of the casing for sliding movement into and out of the same, comprising lateral side flanges extending along the upper edges of the sides of the drawer, longitudinal guide grooves in the sides of the casing in which said flanges are slidably fitted, a pair of rollers mounted on opposite sides of the drawer adjacent to the lower rear corners of said sides, and a pair of channel guide tracks countersunk in the sides of the casing to extend parallel with said guide grooves, said rollers being fitted in and rotatable along said guide tracks, one of said guide tracks being of right-angled form in cross-section with a completely open side to permit side play of the roller therein inwardly and outwardly of said track, and the other of said guide tracks having sides confining the roller there-between and preventing side play of the roller in the guide track.

2. In combination, a casing having sides, a drawer having sides and a bottom, and means to mount said drawer on the sides of the casing for sliding movement into and out of the same, comprising lateral side flanges extending along the upper edges of the sides of the drawer, longitudinal guide grooves in the sides of the casing in which said flanges are slidably fitted, a pair of rollers mounted on opposite sides of the drawer adjacent to the lower rear corners of said sides,

and a pair of channel guide tracks countersunk in the sides of the casing to extend parallel with said guide grooves, said rollers being fitted in and rotatable along said guide tracks, one of said guide tracks being of right-angled form in cross-section with a completely open side to permit side play of the roller therein inwardly and outwardly of said track, and the other of said guide tracks having sides confining the roller there-between and preventing side play of the roller therein, and a pair of anti-friction rollers at the front ends of said grooves mounted on the sides of the casing level with the bottoms of said grooves, and adapted to support said side flanges.
